[57] CLAIM

The ornamental design for a cab fairing for trucks, as shown and described.

DESCRIPTION

FIG. 1 is a perspective view of a cab fairing for trucks showing my new design, it being understood that the broken lines are for illustrative purposes only and form no part of the claimed design;

FIG. 2 is an enlarged front elevation view thereof;

FIG. 3 is an enlarged rear elevation view thereof;

FIG. 4 is an enlarged side elevation view taken from one end, the other side being a mirror image thereof;

FIG. 5 is an enlarged top plan view thereof;

FIG. 6 is an enlarged bottom plan view thereof.

FIG. 7 is a perspective view of a second embodiment of a cab fairing device for trucks showing my new design, it being understood that the broken lines are for illustrative purposes only and form no part of the claimed design;

FIG. 8 is an enlarged front elevation view of FIG. 7;

FIG. 9 is an enlarged rear elevation view of FIG. 7;

FIG. 10 is an enlarged side elevation view of FIG. 7 taken from one end, the other side being a mirror image thereof;

FIG. 11 is an enlarged top plan view of FIG. 7;

FIG. 12 is an enlarged bottom plan view of FIG. 7.
